UNITED STATES PATENT OFFICE.

JUAN FERNANDEZ KNOCK, OF LEWISTOWN, ILLINOIS.

FUEL-SAVER.

1,351,855.

Specification of Letters Patent.

Patented Sept. 7, 1920.

Application filed August 8, 1918. Serial No. 248,986.

To all whom it may concern:

Be it known that I, JUAN FERNANDEZ KNOCK, a citizen of the United States of America, residing at Lewistown, in the 5 county of Fulton and State of Illinois, have invented new and useful Improvements in Fuel-Savers, of which the following is a specification.

The purpose of the invention is to provide 10 means to be used in conjunction with heating apparatus whereby the products of combustion are required to pass over a tortuous path to the chimney, there being devices associated with the said means, so that the heat 15 radiated by the said products of combustion may be conserved and conducted to points where it is desired to utilize the same.

A further purpose of the invention resides in the provision of a fuel saver which 20 is comparatively simple in construction, durable and effective in operation and inexpensive to manufacture and place on the market.

Other and further purposes of the invention appear in the following description 25 wherein the same is set forth in detail.

To the exact construction in which it is shown and described, the invention is not to be restricted. The right is claimed to 30 make any changes or alterations that the actual reduction to practice may suggest, provided these changes and alterations are compatible in spirit with the subjoined claim.

35 The figure is a view partly in section and partly in elevation showing the application of the invention to the ordinary heating stove.

The invention is shown applied to the 40 ordinary heating stove 1 carried upon the floor 2 which is presumed to be the floor of the room which the stove is intended to heat. Between the stove and the chimney 3, there is positioned a casing 4 having the shape 45 preferably of a rectangular parallelepiped. On the interior this casing 4 is divided into compartments 5, 6, 7 and 8, the compartments 5 and 7 being accessible to the doors 9 and 10. The compartments 5, 6 and 7 are 50 formed in a supplemental casing 11 carried interior to the casing 4.

The pipe 12 through which the exhaust gases pass on their way to the chimney 3 is provided with a down leg 13 which passes 55 through the top of the casing 4 adjacent that end nearer the stove 1 and this down

leg communicates with the compartment 5 through the top of the casing 11. Interconnecting the compartments 5 and 6 there is a tubular U-shaped member 14 and a similar member 15 interconnects the compartments 6 and 7 from the latter of which there rises a pipe 16 which passes through the top of the casing 4 and connects with the chimney 3, a damper 17 being carried in the 60 horizontal leg of this pipe 16.

Connected with the top of the casing 4 and preferably adjacent the center of the latter, there are the pipes 18 which communicate with the compartment 8 of the 65 casing.

In the operation of the invention, the products of combustion such as smoke and burnt gases pass through the pipe 12 and its down leg 13 into the compartment 5, thence 70 through the tubular member 14 into the compartment 6, thence through the tubular member 15 into the compartment 7 from which last compartment they pass through the pipe 16 and through the chimney 3 to the 75 atmosphere. In this circuitous or tortuous path of the gases, the heat that is contained in them is radiated through the down leg 13, the tubular members 14 and 15 and the pipe 16 and a very large percentage of this heat 80 radiation takes place in the compartment 8 from which this trapped or confined heat may pass through the pipes 18 to any part of the house it is desired to use the heat, the pipes 18, of course, being led to the 85 points where it is desired to utilize the heat. 90

The invention having been described, what is claimed as new and useful is:

In a fuel saver, the combination with a heating unit, of a main casing, a supplemental casing interior to the main casing and divided into a plurality of compartments, tubular connections between the compartments of the supplemental casing, a tubular connection between the heating unit 95 and one of the compartments of the supplemental casing, another of the compartments of the supplemental casing having means for connection to a smoke stack, certain of the tubular connections and portions of the 100 others being inclosed within the main casing, and tubular members communicating 105 with the main casing for the purpose specified.

In witness whereof he affixes his signature. 110

JUAN FERNANDEZ KNOCK.
